UNITED STATES PATENT OFFICE.

WILLIAM EDGAR CAUDLE, OF GREENSBORO, NORTH CAROLINA.

BURGLAR ALARM.

Application filed October 26, 1925. Serial No. 64,950.

This invention relates to burglar alarms for use in connection with doors and windows of buildings, one of the objects of the invention being to provide a simple structure of this character which can be installed readily and which does not require the use of an electric current.

A further object is to provide a device which, while in use, will sound an alarm when a window or door is opened.

A still further object is to provide apparatus of this character which can be constructed readily and will not easily get out of order.

With the foregoing and other objects in view which will appear as the description proceeds, the invention resides in the combination and arrangement of parts and in the details of construction hereinafter described and claimed, it being understood that changes in the precise embodiment of the invention herein disclosed may be made within the scope of what is claimed without departing from the spirit of the invention.

In the accompanying drawing the preferred form of the invention has been shown.

In said drawings:—

Figure 1 is a front elevation showing the alarm applied to a window, a portion of the bracket of the alarm being shown in section.

Figure 2 is a side elevation of the bracket portion of the alarm and the parts mounted thereon.

Figure 3 is a plan view of the structure shown in Figure 2.

Referring to the figures by characters of reference 1 designates a base adapted to be mounted on a bracket 2 which can be attached to the upper portion of a window frame or door frame. In the present instance a window frame has been shown at F with the bracket attached thereto. Mounted on the bracket and secured thereto in any manner desired is an alarm in the form of a bell 3 of that type adapted to be sounded by the depression of a button 4 supported above the bell. A standard 5 is secured to the bracket and pivotally connected to the upper end thereof is a lever 6 the free end of which is slotted as at 7, so as to straddle and slidably engage a threaded stem 8 secured to and extending upwardly from the base 1. On this stem is

a coiled spring 9 supported by a nut 10, this nut being mounted on the stem.

A cord indicated at 11 is connected at one end to the lever 6 and extends downwardly through an aperture 12 in the base 1. This cord is then guided under a guide pulley 13 suitably located on the frame F and the end of the cord is attached to the window sash W or other movable structure.

Obviously, with the parts attached to the window as shown the movement of the window from its closed position will result in the cord 11 pulling downwardly on lever 6. Thus the button 4 would be depressed and the bell 3 sounded.

In Figure 1 a cord 14 has been shown stretched across the sash one end of this cord being attached to the window sash W while the other end portion is guided in a screw eye 15 and provided with a hook 16 loosely engaging a portion of the cord 11. This cord can be a very fine but strong one or can be in the form of a fine wire which would not be visible through the window under ordinary conditions. Thus, should one of the lights be removed from the sash any one attempting to pass through the same or to reach therethrough would necessarily press against the cord 14 so that it would pull through the hook 16 upon cord 11 and thus sound the alarm.

While the structure has been shown assembled with a window it is to be understood that the same could also be applied to a door. Furthermore a single bell could be coupled to a series of windows or doors so that the opening of any one of them would result in the sounding of the alarm.

It is to be understood that each time the cord 11 is pulled downwardly lever 6 will compress spring 9 so that when the cord is released the lever will be returned to its normal or raised position by the spring.

It is to be understood of course that the alarm herein described could be used for purposes other than those heretofore set forth. For example the operating cord could be extended to an automobile located outside of a building or to the doors or windows of an out building. Thus the alarm would be sounded should an attempt be made to remove the automobile or to enter the out building.

What is claimed is:—

1. A burglar alarm including a bell, a

depressible button for actuating the same, a member normally engaging the button, flexible actuating means providing a constant connection between the said member and a window or the like, and spring means for holding the connection constantly taut.

2. A burglar alarm including a bell, a depressible button for sounding the same, 5 a lever normally engaging the button, adjustable yielding means for normally sup-

porting the lever, a flexible actuating device connected to the lever for attachment to a window or the like, a guide for the actuating device, a second actuating device for 15 attachment to a window or the like, and a slip connection between the two actuating devices.

In testimony that I claim the foregoing as my own, I have hereto affixed my signature.

WILLIAM EDGAR CAUDLE.
